UNITED STATES PATENT OFFICE.

STEELE F. GILMORE, OF INDIANAPOLIS, INDIANA.

METHOD AND DENTAL DEVICE FOR REGISTERING BITES.

Application filed October 3, 1927. Serial No. 223,584.

This invention relates to a dental device particularly adaptable for use in connection with the making of artificial teeth.

The principal object of the invention is to obtain central occlusion, or the natural rest position of the mandible, preparatory to the construction of a set of artificial teeth.

A further object of the invention resides in the provision of such a device as will automatically form the curve of Spee, or compensating curve, registering the individual movements of the condyle, and obtaining facebow measurements, all in one operation.

More specific features of the invention will be noted from the specifications and claims as hereinafter set forth.

The full nature of the invention will be understood from the accompanying drawings and the following description and claims:

20 Fig. 1 is a central vertical section taken thru a portion of the jaw showing the device in rest position. Fig. 2 is a plan view looking down upon the device when removed from the jaw.

25 In the drawings there is shown an upper jaw 10 and a lower jaw or mandible 11, with the gums 12 protruding inwardly therefrom. Positioned over the gums there is a mass of prepared wax or substantially plastic material 13 and 14.

30 The device comprises a pair of concave by convex thin metal plates 15 and 16. Said plates are formed with surfaces of the same curvature and are positioned between the 35 gums and the plastic material 13 and 14 so that the concave surfaces of both plates face the upper jaw and the convex surfaces the lower jaw. The plates in outline, as shown in Fig. 2, conform substantially to the curvature of the gums, and, when in operative position, protrude substantially beyond the same. On the exterior surfaces of each of the 40 plates, when positioned together, there are curved ribs 17 protruding therefrom adapted 45 to be embedded in the plastic material 13 and 14. Also there are provided reinforcing ribs 18 for strengthening the plates and maintaining them in conjunction with the ribs 17 in their proper form.

50 Protruding outwardly from the plates and positioned slightly to one side thereof there are a pair of tongues 19 and 20 forming therebetween the slot 21. Said tongues are so arranged as to protrude from the front of

the mouth when the plates are mounted between the jaws. 55

For the purpose of clamping the plates in their adjusted position after they have been manipulated, as hereinafter set forth, there is a clamp 22 provided with a set screw 23 60 which is adapted to clamp over the ends of the tongues 19 and 20 of both plates for securing them rigidly in adjusted position with respect to each other. Said clamp 22 is provided with a suitable projection 123 65 with set screw 24 cooperating with an opening 122 therethru into which the rod 25 of a facebow may be secured.

In operation, the usual bite waxes 13 and 14 are formed and inserted in the patient's mouth and corrected for height and fullness in the usual manner. With the prepared bite waxes warmed to a soft or yielding temperature, after having been so corrected, they are reinserted into the mouth and the plates 15 70 and 16 are superimposed with respect to each other and placed between the warm bite waxes. The patient is then directed to close the mouth, with just sufficient force to compel the warm bite waxes to take the curved 75 form of the plates 15 and 16, the ribs or ridges 17 becoming embedded therein. During this operation, the clamp 22 is used to maintain the plates in their proper position. The clamp is then removed and the patient is instructed to keep the plates in contact with a slight pressure, and move the mandible or lower jaw 11 in its protrusive, retrusive, right, left and lateral positions. This is continued until the patient finally arrives at the 80 natural tired rest position of the mandible. The patient is then instructed not to move the jaw, and the clamp 22 is again mounted in place and the plates are then locked in position. If the dentist then chooses to do so, 85 the facebow measurements may be taken by inserting the rod 25 of the facebow of the usual and well-known type in place and clamping it by the set screw 24. The plates are then removed from the mouth, either with 90 or without the bite waxes, since the ribs 17 have registered their position with respect thereto so as to permit reassembling. The 95 entire assembly of the plates and the bite waxes, and if desired, the facebow, are 100 installed in the usual type of articulating frame in the manner well known.

The clamping member 22 is then removed,

and the mechanical condyles of the articulating frame are adjusted to correspond with all the movements of the natural condyles of the patient, as recorded in the wax bites and the position of the plates with respect to each other.

It will be readily understood by those familiar with dental practice, that by this method of obtaining occlusal data, the device operates in copying the individual movements of the mandible in a manner similar to the action of the pantograph. Thus orientation, the anterior component, are faithfully and automatically recorded by the position and action of the plates in the articulator. Thus the articulator is readily adjusted to correspond to the particular formation and each of the patient's jaws, whereby the construction of artificial teeth therefor may be readily accomplished.

The invention claimed is:

1. A device of the character described comprising a pair of concave by convex bite plates with surfaces of substantially the same curvature so as to seat one within the other, said plates being adapted to have sliding contact in all directions, and means for clamping said plates in adjusted position.
2. A device of the character described comprising a pair of concave by convex plates having substantially the same curvature and adapted to seat one within the other for permitting relatively sliding movements in all directions, means formed on said plates for engaging and registering them with a suit-

able plastic material, and means for locking said plates in adjusted position with respect to each other.

3. A device of the character described comprising a pair of concave by convex plates having substantially the same curvature and adapted to seat one within the other for permitting relatively sliding movements in all directions, means formed on said plates for engaging and registering them with a suitable plastic material, projections formed on said plates and extending outwardly therefrom, and a clamping member adapted to clamp said projections together for securing said plates in their relative adjusted position.

4. In a device of the character described, the combination with the upper and lower jaws of the patient, of a pair of concave by convex plates having substantially the same curvature of surface, adapted to seat one within the other and permitting a sliding movement therebetween in all directions, bite waxes positioned between said plates and jaws, means formed on said plates for engaging and registering with said bite waxes, and means for locking said plates in adjusted position after the patient has caused said jaws to be moved in all directions and brought to natural rest position, whereby the central occlusion, curve of Spee and individual movements of the condyle will be registered by the relative positions of said plates and their action upon said bite waxes.

In witness whereof, I have hereunto affixed my signature.

STEELE F. GILMORE.
